UNITED STATES PATENT OFFICE.

WILLIAM H. FARRELL, OF SOUTH BETHLEHEM, PENNSYLVANIA.

SPARK-PLUG.

1,142,511.

Specification of Letters Patent.

Patented June 8, 1915.

Application filed January 25, 1915. Serial No. 4,359.

To all whom it may concern:

Be it known that I, WILLIAM H. FARRELL, a citizen of the United States, residing at South Bethlehem, in the county of Northampton and State of Pennsylvania, have invented a new and useful Spark-Plug, of which the following is a specification.

The present invention appertains to spark plugs for internal combustion engines and 10 the like, and aims to provide a novel and improved construction of a spark plug.

It is the object of this invention, to provide a spark plug comprising such a unique assemblage of the component elements, that 15 the efficiency and serviceability of the plug will be enhanced, and whereby the objectionable characteristics of common spark plugs will be eliminated or reduced to a minimum.

20 As a more specific object, the invention aims to provide a spark plug of such construction, that the central conductor may warp or become distorted, due to the heat to which the plug is subjected in use, without 25 the liability of the impairment of the device, the insulation or core also being so formed as to accommodate the conductor, and to avoid the breakage of the porcelain or insulator due to the expansion and contraction 30 of the parts.

Another object of the invention is to provide a spark plug having means for reducing to a minimum the carbonizing or corrodng of the active parts.

35 It is also within the scope of the invention, to provide a spark plug of comparatively simple, non-encumbering and inexpensive construction, which will be convenient, practical and thoroughly efficient in 40 use.

With the foregoing and other objects in view which will appear as the description proceeds, the invention resides in the combination and arrangement of parts and in 45 the details of construction hereinafter described and claimed, it being understood that changes in the precise embodiment of the invention herein disclosed can be made within the scope of what is claimed without 50 departing from the spirit of the invention.

The invention is illustrated in its preferred embodiment in the accompanying drawing, wherein—

55 Figure 1 is a longitudinal central section of the improved spark plug. Fig. 2 is a

cross section thereof taken on the line 2—2 of Fig. 1.

The present spark plug embodies a tubular body or shell 1, constructed of suitable metal, and adapted to be threaded into the aperture or opening of a hydrocarbon engine cylinder or the like. The outer end portion 2 of the bore of the shell 1 is of largest diameter, is of uniform diameter, 60 and is threaded, while the other or lower end portion 3 of the sleeve bore is of smaller diameter, and is tapered from the shoulder 4 between the portions 2 and 3, to the lower or inner end of the shell. The shoulder or 65 ledge 4 faces upwardly or outwardly.

A pair of diametrically opposite angular or L-shaped electrodes 5 are carried by the lower or inner end of the shell 1, certain arms of the electrodes 5 being engaged into 70 the lower end of the shell 1 at diametrically opposite points, and the other arms projecting toward the axis of the shell at vertically or longitudinally spaced points, to provide the sparking terminals or tips 6. One 75 sparking terminal 6 terminates short of the axis of the shell 1, while the other sparking terminal intersects the axis of the shell beyond or below the first mentioned sparking terminal, as clearly apparent by reference 80 to Fig. 1.

The core or insulation comprises lower and upper sections or parts 7 and 8, which are constructed of porcelain or other dielectric material. The lower section or part 90 7 of the core is tapered downwardly and fits tightly within the tapered portion 3 of the sleeve bore, the upper end of the section or part 7 being flush with the internal shoulder or ledge 4 of the shell. The upper section 95 or part 8 of the core is tapered upwardly and extends snugly through the tapered bore of a gland or bushing 9 threaded into the upper end portion 2 of the sleeve bore, whereby when the gland or bushing 9 is 100 threaded downwardly, it will move the section or part 8 of the core downwardly to proper position, and hold it in place. The sections or parts 7 and 8 of the core are in alignment or coaxial, and are concentric or 105 coaxial with the shell 1. The adjacent or meeting ends of the parts of the core are spaced apart, whereby the said sections or parts may move toward each other or longitudinally relative to one another, without 110 danger of breakage, the sections or parts, however, in being seated within the shell

and bushing, respectively, will hold them against excessive separation.

The central conductor of the plug, like the insulation or core, comprises two parts or sections, one being carried by each of the sections or parts of the core. Thus, the conductor comprises the lower and upper sections 10 and 11, which jointly provide the stem or shank through the center of the 10 plug, and constituting the central conductor. The lower section 10 of the conductor is tubular or provided with a longitudinal bore 12, the tubular section 10 being engaged centrally through the lower section 7 of the 15 core, and having a head 13 at its upper end seating upon the upper end of the section or part 7 of the core. The head 13 is provided with an upper rounded socket or recess 14, and a retaining nut 15 is threaded upon the 20 lower end of the tubular conductor section 10 and bears against the lower end of the core section 7 to clamp the tubular conductor section 10 tightly in place, to prevent its longitudinal movement relative to the 25 core section 7.

A pencil or pin 16, preferably constructed of hard zinc or an equivalent alloy, is fitted tightly within the bore 12 of the tubular conductor or section 10, and its lower end 30 protrudes to provide the lower sparking terminal of the conductor, which projects toward or terminates short of the sparking terminals 6 of the shell 1. It is to be noted in this connection that one of the sparking 35 terminals 6 projects toward the tip of the sparking terminal of the conductor in the plane of the said tip, while the other sparking terminal 6 is disposed beyond or below said plane and projects across the tip of 40 the sparking terminal of the conductor, so that both of the sparking terminals 6 are arranged practically the same distance from the tip of the pencil or pin 16, but are arranged at different positions relative thereto, 45 to assure of the proper action of the plug, and to avoid misfiring of the engine. The pencil or pin 16 being constructed of hard zinc or equivalent material, will reduce the corroding to a minimum, and will also prevent 50 the crustation of the electrodes which would impair the efficiency of the plug.

The upper section 11 of the conductor is in the form of a rod engaged longitudinally or axially through the upper core section 8, 55 a nut 17 being threaded upon the lower end portion of the section or rod 11 and being seated within a recess 18 provided in the lower end of the core section 8. The lower end of the section or rod 11 protrudes beyond 60 the nut 17 to provide a finger 19, the tip of which is rounded and fits snugly within the rounded socket or depression 14 of the head 13. A cap or cup shaped nut 20 is threaded upon the upper end portion of 65 the section or rod 11 of the conductor and

engages over the upper end of the core section 8, while a lock nut 21 is threaded upon the rod 11 above the nut 20 to bind the relative parts in place after they have been adjusted.

Washers 22 of asbestos or other dielectric or non-conducting material, are disposed between the adjacent ends of the core sections 7 and 8 so as to be clamped therebetween and to surround the adjacent or contacting ends of the sections 10 and 11 of the central conductor to prevent the grounding of the central conductor, or the establishment of a cross circuit or shunt between the outer conductor or shell 1, and the central 75 conductor. The washers 22 are preferably seated upon the shoulder 4, and being compressible, will allow the core sections 7 and 8 to move toward one another, so as to relieve the porcelain sections or parts of injurious strains.

The lower end portion of the tubular section 10 of the conductor is preferably provided with an aperture 23 to provide a vent, whereby the carbonizing of the central conductor and its sparking terminal or electrode will be minimized.

The present plug eliminates the excessive strains upon the insulating core, which not infrequently has resulted in the breakage of the core in present day spark plugs embodying a one-part core, and having a one-part central conductor engaged therethrough. In the present device, the sections or parts of the core and central conductor may move 90 slightly relative to one another, under the conditions to which the plug is subjected in use, and the ball and socket joint or connection between the sections or parts of the central conductor, provided by the interengaging rounded finger 19 and socket 14 of the conductor sections, will enable the conductor sections to flex or shift laterally slightly relative to one another, to compensate for any longitudinal movement or expansion of the core and metallic conductor sections, without the liability of the conductor or sections separating.

The pin or electrode 16, the lower or inner end of which provides the sparking terminal carried by the central conductor, may be adjusted longitudinally within the tubular conductor section 10, to take up for wear, or to adjust the gap between the sparking terminals of the shell and central conductor. As above intimated, the tubular section 10 of the central conductor is fixed relative to the lower core section 7, whereas the upper section or rod 11 of the central conductor is adjustable so as to properly cooperate with the upper end or head 13 of the lower section 10 of the conductor. To adjust the section or rod 11, the upper nuts 20 and 21 are first loosened, and the lower adjusting nut 17 is then screwed to proper 115 120 125 130

position upon the rod or section 11, so that the projecting finger or portion 19 of the rod 11 will be of sufficient length to properly engage the socket 14 of the head 13. 5 The nut 20 is then tightened, after which the locking or binding nut 21 is tightened to clamp the rod 11, the nuts 17 and 20 being held against accidental movement. It will be observed that the upper end portion 10 or head 13 of the section 10, and the nut 17 and lower end portion of the rod or section 11 are housed within the asbestos or insulating washers 22 and the lower recess 18 of the upper core section 8. 15 In order to prevent the carbonizing of the lower portion of the section or member 10, the same is provided with a longitudinal auxiliary bore 23 extending from its lower end adjacent the pin or electrode 16, where- 20 by the gases may circulate within the auxiliary bore or recess 23 for the said reasons.

What is claimed is:

1. A spark plug embodying a shell, a core comprising a pair of sections secured 25 therein, a central conductor comprising a pair of sections engaged through the core sections, one end of one conductor section having a head bearing against the end of the respective core section, nuts threaded

upon the end portions of the other conductor section and bearing against the respective core section to hold the second mentioned conductor section at its adjusted position, one end portion of the second mentioned conductor section projecting from the 30 respective nut, the said head having a rounded socket receiving the said end portion of the second mentioned conductor section, and a nut threaded upon the other end portion of the first mentioned conductor 35 section and bearing against the respective core section.

2. A spark plug embodying a shell, an insulating core therein, a tubular conductor extending through the core, and an electrode pin extending through the tubular conductor, the tubular conductor having an auxiliary bore extending from one end adjacent the said pin, and the pin projecting beyond the said end of the conductor. 45

In testimony that I claim the foregoing as my own, I have hereto affixed my signature in the presence of two witnesses.

WILLIAM H. FARRELL.
